UNITED STATES PATENT OFFICE.

JOSEPH L. SWEET, OF ATTLEBOROUGH FALLS, MASSACHUSETTS.

APPENDAGE FOR ORNAMENTAL CHAINS.

SPECIFICATION forming part of Letters Patent No. 331,743, dated December 1, 1885.

Application filed April 7, 1883. Serial No. 90,910. (No model.)

To all whom it may concern:

Be it known that I, JOSEPH L. SWEET, of Attleborough Falls, in the county of Bristol and State of Massachusetts, have invented a new and useful Improvement in Chain-Tips, 5 of which the following is a specification.

My invention relates to chain-tips which are commonly provided at the ends of watch-chains to form a connection between the chain proper and the hook or snap at the end thereof; and the object of the invention is to provide a chain-tip of handsome appearance which may be made at less cost than those having their opposite faces ornamented by 15 hand-engraving.

The invention consists in a chain-tip composed of struck-up or embossed ornamental plates of corresponding form, and a band or frame interposed between the plates, and to 20 the edges of which the plates are secured, each plate having its edge portion offset slightly, so as to produce a rim or flange corresponding in form to and fitting the band and forming on the outer faces of the plates sunken panels 25 within which any desired design or ornamentation is produced. This construction is particularly desirable for chain-tips made of rolled plate, because by striking up or embossing the plates the thickness of the gold 30 plate is left unimpaired, and the gold plate is not cut nearly or quite through, as it often is by hand-engraving.

In the accompanying drawings, which is made to an enlarged scale, Figure 1 represents a piece of metal having an ornamental design produced thereon by pressing or stamping. Fig. 2 represents the same piece of metal cut to the desired outline and adapted to form one face of the tip. Fig. 3 is a section on the dotted line xx , Fig. 2; and Fig. 4 40 is a perspective view, and Fig. 5 a sectional view, of the completed tip.

Similar letters of reference designate corresponding parts in all the figures.

The tip is composed of a band or frame, B, 45 and struck-up or embossed ornamental plates A A, applied and secured to opposite sides thereof.

The band or frame B may consist of a strip 50 of thin metal of proper width bent to the desired shape and having its ends soldered together. The plates A are of the same outline

as the band or frame B, and have any desired ornamental configuration or design produced in them by stamping or pressing with dies. 55

In producing each struck-up plate A, I take a piece of metal, A', of sufficient size, and by stamping or pressing with dies I produce an ornamental design or figure, a, therein, as shown in Fig. 1. The metal will generally be 60 thin, and hence those parts of the ornament which are in intaglio on the face will be in relief on the back, and vice versa. After once making the dies the cost of ornamenting the metal will be almost nothing. In the piece of 65 metal A' here shown there is formed a sunken panel, b, in which is the ornamental design a in relief. Subsequently the piece or plate A is cut from the piece A' and to the form shown in Fig. 2. The line on which the surplus 70 metal is cut or trimmed off is just outside the edge of the panel b, leaving a rim or flange, c. (Shown clearly in Fig. 3.) The band or frame B is of such size that the flange c will lap over its edge and be flush with the exterior 75 outline of the said band or frame, as shown best in Fig. 5. The rim or flange c, which corresponds in shape to and overlaps the edge of the frame or band B, is offset slightly beyond the portion b of the plate A, and thereby 80 there is produced on the inner side of the plate a projection, which enters within the band or frame B, and on the outer side of the plate a sunken panel, b, within which the design appears. The two pieces A A are secured to 85 the band or frame B. The band or frame B may also be ornamented by stamping or pressing with dies. The strip from which the band or frame is produced may be thus ornamented.

Not only can chain-tips be made very cheaply according to my invention, but when made of rolled gold plate or other forms of plated metal the thickness of plate will remain unimpaired at every part, and hence will wear 90 longer than when hand-engraved. 95

By my invention I am enabled to dispense entirely with hand-engraving on chain-tips, or to greatly reduce the quantity of hand-engraving, for it is obvious that a small amount of hand-engraving might be performed in connection with the ornamentation produced by stamping or pressing. 100

What I claim as my invention, and desire to secure by Letters Patent, is—

The ornamental chain-tip herein described, consisting of the struck-up or embossed ornamental plates A A, of corresponding form, and the band or frame B, interposed between 5 the plates and to the opposite edges of which the plates are secured, each plate A having its edge portion offset slightly, so as to produce a rim or flange, c, corresponding in form

to and fitting the band B, and forming on the outer face of the plate a sunken panel, b, substantially as herein set forth.

JOSEPH L. SWEET.
